UNITED STATES PATENT OFFICE.

AUSTIN E. RUDDOCK AND EPHRAIM E. E. BAILEY, OF HAVERHILL, MASSACHUSETTS, ASSIGNORS TO T. S. RUDDOCK & SON, OF SAME PLACE.

MACHINE FOR FEATHER-EDGING SOLES FOR BOOTS AND SHOES.

SPECIFICATION forming part of Letters Patent No. 398,282, dated February 19, 1889.

Application filed October 30, 1888. Serial No. 289,572. (No model.)

To all whom it may concern:

Be it known that we, AUSTIN E. RUDDOCK and EPHRAIM E. E. BAILEY, both of Haverhill, in the county of Essex and State of Massachusetts, have invented certain new and useful Improvements in Machines for Feather-Edging Soles for Boots and Shoes, of which the following is a specification.

This invention relates to machines for "feather-edging" the outer soles of boots and shoes in which the stitches connecting the outer sole to the upper and inner sole are laid in a channel formed in the outer sole.

The invention has for its object to provide devices whereby the outer surface of the outer sole may be brought to a thin edge to give the shoe a neat appearance without cutting away any of the outer surface of the sole, the grain-surface of the outer sole being extended to the edge of the sole as when the edge is not reduced in thickness.

To this end our invention consists in the improvements which we will now proceed to describe and claim.

Of the accompanying drawings, forming a part of this specification, Figure 1 represents a side elevation of the portion of a machine having our improvements attached thereto. Fig. 2 represents an end view of the same, parts being shown in dotted lines for the sake of clearness of description. Fig. 3 represents a view of the side opposite to that shown in Fig. 1. Fig. 4 is a perspective view of the knife. Fig. 5 is a perspective view of the guide. Fig. 6 represents a sectional view of an outer sole after having been operated upon by our improved machine.

The same letters of reference refer to the same parts in all of the figures.

In the drawings, *a* represents a portion of a machine to which our improvements may be attached.

b represents a feed-roll attached to a shaft, *c*, journaled in bearings in said machine and adapted to be rotated by any suitable means.

d represents a knife adjustably secured to the machine, having a cutting-edge projecting above the upper portion of roll *b*. Said cutting-edge is preferably curved or slanted and formed to cut from the bottom of the channel to and through the flesh side of a sole and to

remove a part of the outer edge of said flesh side. The knife *d* is provided with a slot, *e*, through which passes a bolt, *f*, screw-threaded into the frame of the machine. This construction permits the knife to be easily adjusted, as will be readily understood by reference to Fig. 1.

g represents a supporting-roll journaled in bearings in a block, *h*, attached to an arm, *i*, of the machine, and adapted to raise or lower according to the thickness of the sole to be operated upon. The sole to be operated upon or "feather-edged" is placed between the feed-rolls *b* and *g*, which operation raises roll *g* and guide *j* so that said guide coincides with the channel in said sole into which it is adapted to enter, as shown in Fig. 5. The said guide *j* is adjustably attached to the block *h*, and is arranged thereon and in the machine so as to be in front of the cutting-edge of knife *d*. Said guide is provided with a foot, *k*, having an offset, *l*, formed to enter the channel cut in the edge of the sole, the arrangement being such that the feed-roll *b* crowds the sole toward said guide during the cutting operation, causing the projecting portion *l* of the guide to come in engagement with the bottom of the channel, thus effecting an accurate cutting action of the knife. The upper part of guide also raises the channel and prevents it being cut by the knife during the operation of feather-edging. (See Fig. 5.)

By the means above described we are so enabled to cut away the flesh side of the outer sole as to permit the grain-surface *m*, Fig. 6, of an outer sole to be extended beyond the edge of the flesh side *n* of the same, as will be readily seen. We do not limit ourselves to the machine here shown and described, to which our improvements are attached, as they may be applied to any suitable machine for feather-edging soles without departing from the spirit of our invention.

In Fig. 5 we have shown a perspective view of the guide *j* and a portion of a sole, *j'*, before being operated upon. Said sole has a channel, *l'*, into which the projection *l* of the guide enters, the arrangement being such that the channel-flap is held in a raised position, as shown, which prevents the same from being cut by the knife *d* during the trimming

operation. This projecting portion *l* of the guide, whereby the liability of cutting the channel during feather-edging is obviated, constitutes an important feature of our invention.

5 We claim—

1. In a feather-edging machine, the combination, with the work feeding and supporting rolls, of the guide formed to enter the channel cut in the edge of the sole and keep the channel-flap elevated and the curved or slanted knife arranged behind said guide and formed to cut from the bottom of the channel to and through the flesh side of the sole, and
- 10 15 to remove a part of the outer edge of said flesh-sole, all arranged and operating as described.
2. In a feather-edging machine having suit-

able work supporting and feeding devices, the guide having a projection to enter the channel in the sole and elevate the flap thereof, combined with the knife having a curved and beveled cutting-edge, and arranged behind the guide and adapted to enter the work below the flap and feather-edge the sole, substantially as described.

20 25 In testimony whereof we have signed our names to this specification, in the presence of two subscribing witnesses, this 8th day of August, A. D. 1888.

AUSTIN E. RUDDOCK.
EPHRAIM E. E. BAILEY.
